Rudolf Hofer, Berlin, Germany, assignor to Tele-funken Gesellschaft für Drahtlose Telegraphie m. b. H., Berlin, Germany, a corporation of Germany

Application May 7, 1938, Serial No. 206,578
In Germany May 20, 1937

14 Claims. (Cl. 179—171.5)

This application concerns a method of and a circuit for the modulation of high frequency waves with improved efficiency.

Various methods are known by which an economical consumption of power of high frequency transmitters is possible, and more especially of transmitters for telephony. The simplest method of this type which is successfully used in the plate voltage modulation of the transmitter end stage by means of a push-pull class B modulation amplifier. With this method an efficiency of the entire transmitter end stage (high frequency part plus audio frequency part) can be attained which is practically independent of the degree of modulation. This method has, however, the disadvantage of a larger amount of audio frequency apparatus causing in many cases inconveniences, and in the first place the weight of the required modulation transformer is too high. Furthermore, the efficiency of the transmitter can be improved by the modulation method of Chireix, but the efficiency of this method decreases rapidly with an increase in the degree of modulation, and its control of operation is extremely difficult. In another modulation method also already known the transmitter comprises two stages operating in parallel into a common load and of which one stage transmits only these high frequency amplitudes lying above the mean carrier value while the other one transmits only the modulation amplitudes lying below said carrier value. In this case, the linearity of the dynamic modulation characteristic is again questionable in case of small degrees of modulation as well as at very high degrees of modulation so that cumbersome arrangements for reducing the distortion for the purpose of improving the quality are necessary.

The object of the invention is to provide a circuit for modulation with improved efficiency whereby the latter is more favorable than in case of the last mentioned method and in which the modulation characteristic is at the same time practically completely straight. In accordance with the invention, the carrier energy of a non-modulated tube stage is delivered to the load and the additional modulation energy is added by means of a stage consisting of one or several tubes connected in series or in parallel to the load, said stage furnishing the load with high frequency energy during the half cycles of the modulation during which the wave amplitude exceeds the carrier amplitude but absorbing high frequency energy from the load during the other half cycles of modulation.

In order to practice this method various modes of construction are possible, two of which will be described in greater detail in the following. The essential point in the two examples of construction resides in that the efficiency of the tube supplying the carrier energy is rendered an optimum, for instance in that the tube operates approximately between a condition of low efficiency with high output and a condition of very high efficiency but low output. Care must then simply be taken that the efficiency of the stage furnishing the modulation power has the same high value or permits at least of attaining a high total efficiency.

15 In describing my invention reference will be made to the attached drawings wherein:

Fig. 1 is a circuit diagram illustrating a modulation system, arranged in accordance with my invention, and comprising a non-modulated carrier amplifier stage coupled to a load with an additional modulator stage for supplying energy to the load and to the output of the amplifier stage when the modulated wave under control of modulating potentials exceeds the carrier amplitude and for absorbing energy from the load when the modulated wave amplitude is less than carrier amplitude.

16 Figs. 2a, 2b, 3, 3a and 4 are graphs and curves used in describing operation of the system illustrated in Fig. 1.

17 Figs. 5, 6, 7, 8 and 9 illustrate modifications of the arrangement of Fig. 1, while;

18 Fig. 10 is a curve illustrating the operation of the modulator in the system.

19 In Figure 1 the tube operating with optimum efficiency and serving for providing the carrier energy is designated by R₁. This tube is so dimensioned as to be capable of furnishing at least twice the average carrier energy. The grid of

20 said tube has the high frequency control potential U_{G1} applied thereto. The plate circuit contains the tuned oscillatory circuit L₁, C₁ through which the upper harmonics are passed to ground. There is placed in parallel to the tube across a

21 tuned series circuit L'₁, L''₁, C'₁, the load such as for instance an antenna R. The series circuit does not represent a resistance for the carrier frequency supplied by the tube R₁. However, the said series circuit transmits across the cou-

22 plings L'₁, LK₂ and L''₁, LK₃ a potential to the anodes of the tubes R₂ and R₃ which serve for supplying the modulation powers and which carry practically no plate current in the non-modulated state. The coupling coils LK₂ and LK₃ are ex-

23 tended into tuned series circuits by means of

capacities CK_2 and CK_3 respectively. In the case of all tubes, blocking condensers CB are inserted between the anodes and the oscillatory circuits, and the plate potentials are applied across choke coils. As in the case of tube R_1 , also in the tubes R_2 and R_3 , the plate circuit contains tuned oscillatory circuits L_2 , C_2 and L_3 , C_3 provided for by-passing the higher harmonics. The tubes R_2 and R_3 are controlled in push-pull at the grid side by the high frequency as well as by the modulation frequency, while their plate circuits are shunted as can be seen from the figure. The tube R_2 has the task of supplying the load R with additional power during the positive half cycles of modulation, that is, when the power supplied to the load is above the normal carrier power, while the tube R_3 produces across the coupling LK_3 , L'_1 a counterpotential in the load circuit during the negative half cycles of the modulation, so that the potential at load R will be decreased. Thus, the tube R_3 consumes only the energy which it receives from the tube R_1 therefore not requiring in general any direct plate potential. Only where very high degrees of modulation appear such as up to 100% will a relatively low direct potential U_2 be of advantage.

I will now describe the operation of the tube R_2 in the upward or positive half cycle of modulation. The negative grid biasing potential U_g blocks the tube almost completely, i. e., the peak of the high frequency potential U_{g2} impressed upon the grid of the tube causes practically no flow of plate current. These conditions are shown in Figure 2a. The working point A of the tube R_2 thus is located in the negative region at the voltage U_g , so that the high frequency amplitude U_{g2} just reaches up to the zero point of the grid potential U_g . The plate current is designated by ia and the characteristic of the tube by S. On the positive half cycle of modulation a voltage U_{m2} is applied to the grid of tube R_2 whereby the working point is shifted in the positive direction. The modulation potential U_{m2} is indicated in dash lines in Figure 2a. During a positive half cycle of modulation, the tube R_2 passes current and thereby applies across the coupling LK_2 , L'_1 a voltage to the load R , said voltage doubling the potential at R in case of 100% modulation. Therefore, the current in the load circuit passing through the load R and tube R_1 will likewise be doubled. The phase of the voltage applied from tube R_2 to the load R must correspond with the phase of the voltage applied from tube R_1 to the load. Since in the circuit shown a phase shift of 90° occurs in the coupling circuits between the alternating-current potential at R and the alternating plate potential of tube R_2 , the exciting voltage U_{g2} applied to the grid side of the tube R_2 must likewise be shifted in phase by 90° with respect to the exciting voltage U_{g1} of tube R_1 . This phase relation is obtained in any manner such as, for example, by a phase shifter between the carrier source and points 2 and 4. When assuming that the direct current plate potential of tubes R_1 and R_2 are equal to each other, such as is generally the case when using a common plate potential source, the coupling LK_2 , L'_1 must be adjusted in such manner that the voltage transmitted from R_1 to R_2 is in the non-modulated state approximately one-half of the direct plate potential U_a .

During a negative half cycle of modulation the tube R_3 will become conducting because the modulation potentials are in opposite phase on the grids of tubes R_2 and R_3 . R_2 is now blocked. The

conditions at tube R_3 are represented in Figure 2b. The biasing grid potential of R_3 is preferably chosen equal to that of tube R_2 , i. e., equal to U_g suitably by using the same voltage source. The alternating grid potential of high frequency is designated by U_{g3} , and the alternating potential of low frequency is designated by U_{m3} . Since the phase of the high frequency potential applied from the tube R_3 to the load is in opposition to the phase of the high frequency potential obtained from the tube R_1 , the tube R_3 consumes the power received from the tube R_1 during the half cycle in which R_3 is conductive. In other words on this part of the modulation cycle R_1 supplies power to R_3 and this said power is converted by said tube R_3 into anode heating losses. This energy produces across the coupling LK_3 , L'_1 in the load circuit a counterpotential by which the load power will be reduced. The current passing through the tube R_1 is diminished thereby and will be equal to zero at 100% modulation, while the alternating plate potential at R_1 remains practically constant.

Figures 3 and 3a show the conditions of the voltages and currents of tubes R_2 and R_3 during an entire modulation cycle (in this case as well as in the remaining part of the description it is assumed that the transmitter is modulated only with a single audio-frequency oscillation; if the modulation consists of a frequency mixture, for instance speech or music, obviously also this mixture can always be divided into parts having positive modulation and parts having negative modulation). The tube R_2 (Figure 3) operates as regards high frequency in equal phase with the voltage supplied by the tube R_1 . The maxima of the current of tube R_2 (shaded areas) correspond with the voltage minima in the half cycles of positive modulation. The direct plate potential is designated by U_a , the alternating plate potential by U_{a2} and the plate current by ia_2 . In the half cycle in which the modulation is downwards no plate current flows in R_2 . The tube R_3 is blocked during the first half cycle (positive modulation) and operates only during the second half cycle (negative modulation). Since, however, in the latter the potentials of tube R_1 and tube R_3 are in opposite phase the current maxima correspond in this latter tube with the voltage maxima. The plate current is designated by ia_3 , the direct plate potential by U_z , the alternating plate potential by U_{a3} . The voltage U_z is at a high degree of modulation necessary only in view of the fact that the alternating plate potential becomes very small or even zero just at the moment in which the tube is passed by the maximum plate current. In this moment a minimum plate potential must exist at the tube and which is approximately equal to the saturation voltage.

The modulation characteristic of the entire circuit depends upon the characteristics of the two tubes R_2 and R_3 . The total characteristic can be made linear by slightly opening the tubes R_2 and R_3 at the grid side in the non-modulated state such as shown in Figure 4. This is done by reducing the bias U_g slightly. In this figure S_2 represents the characteristic of the tube R_2 while S_3 is that of the tube R_3 . Item T represents the average carrier value, i. e., the value corresponding to the non-modulated state. Then even without modulation tube R_2 supplies a certain current amplitude I_{ao} and a certain power which will be consumed by the tube R_3 and is converted into heat. Since the lower bends of the modulation

characteristics of R_2 and R_3 can practically be rendered equal to each other through voltage feed back or countercoupling there will be obtained in a manner similar to the push-pull class B modulation, a resultant straight modulation characteristic if the additional carrier current I_{ao} is properly adjusted.

As regards the value of the necessary power of the tubes, the following can be said: At a modulation of 100% each of the two tubes R_1 and R_2 must be capable of delivering as peak value a power equal to twice the power of the carrier. If in the non-modulated state equal voltages would be furnished from R_1 and transmitted to R_2 and R_3 (voltages of the order of one-half of the direct voltage U_d) then R_2 would, the same as R_3 at the moment of the voltage doubling, have to furnish the same maximum current in order to suppress this voltage. The voltage peaks at the tubes R_1 and R_2 have a value equal to twice that of the direct potential. Therefore, when admitting the same value of the voltage peak also for tube R_3 , the maximum voltage which the tube R_1 delivers to the tube R_3 can approximately be four times as high as the voltage supplied by R_1 to R_2 , because hardly any direct potential exists at R_3 . This voltage transmission can be set by means of the coupling LK_3 , L''_1 . In this case the tube R_3 need have only one-half of the emission of R_2 , hence also only one-half of the actual power as related to the same plate potential. The actual power may even be still lower since voltage peaks occur always in the non-modulated state, so that a higher potential can be applied to the tube. This condition as regards power indicates that the required additional number of tubes is unimportant as regards other modulation circuits.

When utilizing a coupling coil LK_2 and LK_3 which is in part a common coupling coil, the following condition should be borne in mind: As long as the tube R_1 only furnishes current it provides the tubes R_2 and R_3 with voltages across these coupling coils, which voltages are displaced in phase by 90° relative to the control power of U_{g1} of R_1 . Now, if one of the two tubes R_2 or R_3 provides an additional voltage, the said tube causes at the anode of the other tube (R_3 or R_2) a partial voltage which is displaced in phase by 90° relative to the voltage part supplied by R_1 . As long as only one of the two tubes R_2 or R_3 is in operation, this phase displacement is immaterial. During the short time periods of the common operation, the phase displacement, however, has the effect in the two tubes as if said tubes would operate upon a resistor having a small wattless component instead of operating upon an effective resistance. Since, however, during the short time periods of the common operation of the two tubes, the output of power is extremely small as compared with that of the tube R_1 , this condition can practically be neglected.

In the circuit shown in Figure 1 the stage furnishing the additional modulation power (and comprising the tubes R_2 and R_3) is placed in series to the load R . In place of this series connection also a parallel connection may be used in which case special means are provided, however, whereby the tubes operate in common in the desired manner. Such means have in part become already known in the modulation circuit mentioned above in which two stages operating in parallel act upon a common load. The following explanations, therefore, are brief. In

Figure 5 the tubes R_2 and R_3 which are controlled in the same manner as in Figure 1, operate upon a common blocking circuit L_2 C_2 and upon the load R , i. e., they have the same alternating plate potential applied thereto. Hence, the emission of R_3 must be equal to that of R_2 . Between the tube R_1 furnishing the carrier power, and the load, a transformation member is inserted consisting of either a known $\lambda/4$ connection,

5 or as represented in the drawings, of a substitution circuit which is an equivalent of this connection and formed by the inductance L'_1 and capacities C'_1 and C_{K2} . The other reference characters of Figure 5 correspond to those of Figure 1. The carrier tube R_1 operates at optimum efficiency which is accomplished by the combination of the capacity CB and of the parallel resistor R_g . Similar to the transformation member LK_2 and LK_3 in Figure 1, the parallel 10 circuit may also be closed across a transformation member situated between the tube R_1 and the tubes R_2 and R_3 as shown in Figure 6, which in view of the descriptions of the other figures does not require further elucidation. In this last 15 mentioned circuit a tube having diminished power may again be utilized as tube R_3 . Finally, it is also possible to provide a series connection in accordance with Figure 1 and having no transformation member LK_2 , LK_3 as was the case in 20 the parallel connection of Figure 5, whereby the powers of the tubes R_2 and R_3 must again correspond to each other. The tube R_1 which may be as in the prior figures supplies carrier power to L'_1 . This may be done by connecting the output 25 of R_1 to points 16 and 18 of Figure 6.

In a second example of construction which will be described in connection with Figures 7-10, the carrier power is again furnished by a non-modulated tube having a high efficiency, 30 while the stage serving for furnishing the modulation power consists of an amplifier controlled by the modulated high frequency with suppressed carrier. Again, a series connection as well as a parallel connection of this amplifier 35 stage with the load is possible. The series connection is shown in Figure 7 in which R_1 designates the tube furnishing the carrier power and R is the load. As in the foregoing example of construction items L_1 , C_1 represent again a tuned 40 series circuit and L'_1 , C'_2 represent a blocking circuit. The grid biasing potential of tube R_1 adjusts itself automatically to the optimum efficiency of the tube on account of the combination of R_g and CB . The emission of tube R_1 45 must again be so high that a control up to the double value of the carrier power is possible. The tube R_2 has such a grid biasing potential (U_g) applied thereto that it operates with a small steady plate current which is such that 50 the oscillation curve of the tube is practically a straight line. As alternating grid potential U_{g2} of tube R_2 for instance the output voltage of a push-pull modulator may be used in which the high frequency is modulated by the modulation 55 potentials but the carrier is suppressed. Therefore, in the non-modulated state the tube R_2 does not receive alternating grid potential. The plate circuit of tube R_2 contains the tuned oscillatory circuit L_2 , C_2 coupled to the inductance L_1 across an intermediate circuit LK_1 , LK_2 . If 60 the tube R_1 supplies carrier power a voltage will be applied to the anode of tube R_2 across this coupling, said voltage being so chosen by suitable dimensioning of the coupling that it is approximately equal to one-half of the direct plate 65

potential U_a . This latter condition is obviously only true if the direct plate potential of tube R_1 and that of tube R_2 are the same such as will generally be the case when using a common plate voltage source. The tube R_2 must have a high internal resistance in order that the voltage impressed upon the anode of R_2 by the tube R_1 causes a substantial plate current thus avoiding any considerable losses. Since the internal resistance of the tube R_1 is very low due to the limited operation between the state of operation with excessive voltage and that of insufficient voltage, practically the entire side band power is applied from the tube R_2 to the load R . This side band power produces at the circuit L'_1 , C'_1 a resultant voltage whose phase position must correspond with the phase position of the carrier. Since, however, a phase change of 90° occurs in the coupling circuits L_2 , LK_1 , LK_2 , L_1 the said required condition can be attained only if the phase of the alternating grid potential U_{g2} is displaced by 90° relative to the alternating grid potential U_{g1} . The necessary phase displacement may be given to U_{g1} or U_{g2} by known phase shifting means.

Any known phase shifting means such as a simple tuned circuit 40 shown supplying carrier energy to the suppressed modulator may be used. The phase shifting means may be connected as shown diagrammatically in Figure 1.

In the following the operation of the two tubes R_1 and R_2 at modulation will be elucidated: The tube R_1 operates with an alternating plate potential which remains practically constant and whose amplitude has approximately the same value as the direct plate potential. Since, the side band currents furnished by R_2 must flow through the tube R_1 , the alternating plate current of R_1 pulsates in the rhythm of the modulation without the alternating potential of tube R_1 being influenced thereby. Therefore, the efficiency of this tube is constantly favorable. Figure 10 shows the variations of the plate current i_a (shaded areas) and the plate potential of tube R_2 at 100% modulation with a sinusoidal note during an audio-frequency cycle. The alternating potential transmitted from tube R_1 to the anode of tube R_2 is approximately one-half of the direct plate potential. In the figure the voltages and the currents in the half cycle for upward control, i. e., at an increase in power, are shown between 0 and π . The carrier voltage $U_a/2$ is controlled upwards by U_a whereby the current attains its maximum value at the time of the lowest steady plate potential during the high frequency half cycles. Throughout this half cycle the efficiency of the tube R_2 is favorable because the plate current pulses occur when plate current is minimum. During the second half cycle the current maxima of tube R_2 coincide, during the individual high frequency cycles, with the voltage maxima as shown, owing to the phase jump by 180° of the beating of the side band. In view of this fact, the efficiency will be slightly diminished during this half cycle. In the non-modulated state and slightly modulated state the total efficiency of the arrangement still lies approximately at 60-65%.

Figure 8 shows a circuit in which the tube R_2 of Figure 7 is placed in parallel to the load R and not in series thereto as in Figure 7. In Figure 8 for simplicity the carrier suppressed modulator has been omitted. It may be as in Figure 7 and may be connected at points 20 and 22 to

supply side-band energy only to R_2 . The plate circuit L_2 , C_2 of this tube operates in parallel to the load R placed in series to the coil L_1 this operation taking place across a coupling coil LK_1 tuned in conjunction with the coil LK_2 and the capacity CK . This circuit corresponds with the circuit according to Figures 5 and 6. Figure 9 finally shows an arrangement in which the tube R_2 operates likewise in parallel upon the load, whereby however the tube R_1 is connected to the load across an energy line whose length is $\lambda/4$. In both circuits (Figure 8 and Figure 9) the current passing through the tube R_1 varies in the rhythm of the modulation. These current variations are caused by the change of the apparent damping of the load circuit.

In the arrangements of Figures 7-9 the modulation power is furnished by an amplifier tube controlled by the modulated high frequency having the carrier suppressed. However, the tube R_2 may also be substituted by the modulator for suppressing the carrier. If this modulator is a push-pull modulator there can be seen immediately the similarity between the circuit (Figure 1) described in connection with the first example embodying the idea of the invention and the second example. The sole difference resides in that in Figure 1 the one push-pull tube R_3 receives no direct plate potential or only a low potential, while the voltage conditions in the push-pull modulator are symmetrical. This distinction entails an essential difference between the modes of operation of the two circuits.

The invention is in no ways limited to the special circuits shown herein and may be modified in many ways, for instance in that amplifier stages are inserted between the individual tubes, or in that in each stage several tubes operate in parallel for the purpose of increasing the power, etc.

I claim:

1. In a high efficiency carrier wave modulating and amplifying system, a load circuit, a source of carrier waves, an amplifier having an input coupled to said carrier wave source and having output electrodes coupled to said load circuit, a carrier suppressor modulator comprising a pair of tubes having input electrodes coupled to said carrier wave source and having output electrodes coupled by separate circuits to said load circuit and to the output electrodes of said amplifier, means for controlling the amplification of the tubes of said modulator in push-pull relation in accordance with signal potentials, and means for producing a phase relation between the carriers supplied to the inputs of said amplifier and modulator such that the energy supplied by said modulator to said load and to the output electrodes of said amplifier is in phase with the carrier energy on the output electrodes of said amplifier during the positive half cycles of the modulating potentials and is in phase opposition during the negative half cycles of said modulating potentials.

2. The method of modulation which comprises the steps of, producing carrier wave energy, amplifying said carrier wave energy in a first path, modulating said carrier wave energy in a second path at signal frequency to produce sideband energy the phase of which reverses with reversals in the modulation cycle, relatively adjusting the phases of the carriers so that the phase of the sideband energy during a portion of the modulation cycle corresponds to the phase of the am-

plified carrier wave energy, and combining said energies to augment on one-half of the modulation cycle and oppose on the other half of the modulation cycle, and to control the amplification of said carrier energy by said sideband energy.

3. The method of modulation which comprises the steps of, producing carrier wave energy, amplifying the said carrier wave energy in a first path, modulating said carrier wave energy in a second path at signal frequency to produce modulation energy comprising sideband energy the phase of which reverses with reversals in the signal frequency cycle, adjusting the relative phases of the carriers to a value such that the said sideband energy is in phase with the said amplified carrier during a portion of the sideband cycle, and imposing said modulation energy on said amplified carrier energy to control the amplification of the amplified carrier wave energy and simultaneously to augment said carrier on one-half of the modulation cycle and oppose said carrier on the other half of said modulation cycle.

4. In a carrier wave modulating system, a load circuit, a source of carrier waves, an amplifier tube having input electrodes coupled to said carrier wave source and having output electrodes coupled to said load circuit, a carrier suppressor modulator comprising a pair of tubes having input electrodes coupled to said carrier wave source and having output electrodes coupled to said load circuit and to the output electrodes of said amplifier, means including a source of modulating potentials for controlling the amplification of the pair of tubes of said modulator in push-pull relation in accordance with signal potentials, means for biasing the tubes of said pair of tubes by potentials such that their outputs are low in the absence of signal potentials, and means for producing a phase relation between the carrier waves supplied to the input of said amplifier and the inputs of said modulator tubes such that the energy supplied by said modulator tubes to said load circuit and to the output electrodes of said amplifier tube is in phase with the carrier wave energy supplied by said amplifier to said load circuit during the positive half cycles of the signal potentials and is in phase opposition during the negative half cycles of the signal potentials.

5. A system as recited in claim 4 wherein the output electrodes of said amplifier are coupled by a series tuned circuit with said load circuit and wherein the output electrodes of said pair of modulator tubes are coupled with said series tuned circuit to combine said outputs in series in said load circuit.

6. A system as recited in claim 4 wherein the output electrodes of said amplifier tube are connected in a series circuit tuned to the frequency of said carrier wave energy and connected in series with said load circuit and wherein the output electrodes of said pair of tubes of said modulator are connected in parallel and coupled to said circuit series-tuned to the carrier wave frequency.

7. In a wave modulating system, a load circuit, a source of carrier wave energy, an amplifier having input electrodes coupled to said carrier wave source and having output electrodes connected in series to said load, a carrier suppressor modulator arrangement having input electrodes and output electrodes, phase shifting means coupling said input electrodes to said carrier wave source, means coupling said output electrodes to said load and to the output electrodes of said amplifier tube, said coupling being such that the output of said modulator is in series with the

output of said amplifier, means for controlling the amplification of said modulator tube arrangement in accordance with signals whereby wave energy modulated in accordance with modulating potentials is produced therein, and means for biasing said modulating tube system by a potential such that it supplies substantially no energy to said load and the output electrodes of said amplifier in the absence of modulating potential signals.

8. In a carrier wave modulating system, a source of carrier wave energy to be modulated, a source of modulating potentials, a load impedance, a carrier wave amplifier tube having input and output electrodes, means coupling said input electrodes to said source of wave energy, a circuit coupling the output electrodes of said amplifier tube to said load impedance, a pair of modulator tubes each having input and output electrodes, means for impressing wave energy from said source in phase opposition on the input electrodes of said modulator tubes, means for coupling the output electrodes of said modulator tubes in parallel and impressing their output on said load impedance and on the output electrodes of said amplifier tube, means for modulating the impedances of said modulator tubes in phase opposition whereby modulation of said carrier is accomplished with carrier suppression, means for biasing said modulator tubes by a direct-current potential such that their output is substantially zero in the absence of modulating potentials, and means for relatively adjusting the phases of the carrier energy impressed on the input electrodes of said amplifier tube and the carrier energy impressed on the input electrodes of said modulator tubes to a value such that the output of said modulator tubes is in phase with the output of said amplifier tube on the positive portions of the modulation cycle.

9. A system as recited in claim 8 wherein said phase shifting means is included in said means for impressing wave energy from said source on the input electrodes of said modulator tubes.

10. A system as recited in claim 8 wherein said phase shifting means is in said circuit coupling the output electrodes of said amplifier tube to said load impedance.

11. A system as recited in claim 4 wherein said last named means is a line the length of which is substantially equal to one-quarter the length of the carrier waves.

12. A system as recited in claim 8 wherein the output electrodes of said amplifier tube are coupled in series with the load circuit by a circuit series-tuned to the frequency of the carrier waves, and the output electrodes of said pair of modulator tubes are coupled to said series-tuned circuit.

13. A system as recited in claim 4 wherein said coupling between the output electrodes of said modulator tubes and said load circuit and the output electrodes of said amplifier tube includes a coupling tube coupled at its input to said output electrodes of said modulator tubes and at its output to said load circuit and the output electrode of said amplifier tube.

14. In a wave modulating system, a source of carrier wave energy voltage to be modulated, a source of modulating potentials, a load circuit, three electron discharge tube systems each having input and output electrodes, one of said tube systems operating as an amplifier, means coupling said source of carrier wave energy to the

input electrodes of all of said tube systems to excite the same co-linearly by wave energy voltages, said one of said tube systems operating to amplify said wave energy, means coupling said source of modulating potentials to the input electrode of the other two of said tube systems to excite the same in phase opposition by modulating

5 potentials to produce therein voltages of upper and lower sideband frequencies, and means coupling the output electrodes of all of said tube systems to said load circuit to combine said amplified carrier wave voltage and said sideband voltages in series in said load circuit.

RUDOLF HOFER.
